UNITED STATES PATENT OFFICE.

EMMA C. ARNOLD, OF MOUNT CLEMENS, MICHIGAN.

COMFORTER.

1,267,042.

Specification of Letters Patent. Patented May 21, 1918.

Application filed December 7, 1917. Serial No. 206,049.

To all whom it may concern:

Be it known that I, EMMA C. ARNOLD, a citizen of the United States, residing at Mount Clemens, in the county of Macomb and State of Michigan, have invented certain new and useful Improvements in Comforters, of which the following is a specification.

This invention is a comfort or blanket and has for its principal object the provision of simple and efficient means for releasably connecting two sections of the comfort or blanket together, whereby when the device is in use a comparatively long comfort or blanket may be provided for the usual purposes, although when it is desired to easily handle the comfort or blanket with the least amount of energy, the sections may be easily separated for permitting this action.

Another object of this invention is the production of a sectional blanket comfort wherein the padded sections have their ends abutting, although a plurality of flaps are provided which overlap each other and are releasably connected together, thus forming a connection between the sections which will prevent the passage of air currents therebetween, although when it is desired to handle the blanket or comfort for purposes of washing or patching the same with comparative ease, the flaps are disengaged for releasing the two sections from engagement with each other.

A still further object of this invention is the production of a comfort or blanket formed of a sectional construction, wherein one section is provided with a flap extending for a considerable distance therebeyond and having a plurality of securing elements upon each side thereof, while the remaining section is provided with a flap formed thereon at a distance from the end of this particular section, this particular section and flap also being provided with securing means to coöperate with the securing elements upon the first mentioned section and flap, thus permitting the two sections to be releasably united, while the overlapping of the flaps will prevent an air draft through the comfort or blanket at the point of junction of the two sections.

With these and other objects in view, this invention consists of certain novel combi-

nations, constructions, and arrangement of parts as will be hereinafter fully described and claimed.

One practical form of construction and assembly of the present invention will be hereinafter described and is illustrated in the accompanying drawing, in which—

Figure 1 is a plan view of a portion of a comfort or blanket, illustrating the two sections thereof releasably connected together.

Fig. 2 is a longitudinal section through the device, taken on the line 2—2 of Fig. 1, looking in the direction of the arrows.

Fig. 3 is a section taken on the line 3—3 of Fig. 1 looking in the direction of the arrow.

Referring to the accompanying drawing by numerals, it will be seen that the comfort or blanket comprises a primary section 1 and the auxiliary section 2. As herein illustrated, it will be noted that the sections are formed of the covering material 3 having filling 4. While this form of a construction is illustrated, it is obvious that any other suitable form of construction may be employed without departing from the spirit of the invention, for upon referring to the device it will be noted that the novelty resides in the manner of releasably connecting the two sections together.

The primary section 1 has the covering 3 brought together and stitched as indicated at 5 to form a comparatively thick flap 6. This flap 6 is formed upon the primary section 1 at a point at a considerable distance from the end 7 of the primary section. The edge of the flap 6 terminates at a point adjacent the abutting end 7 of the primary section and thus it is obvious that a receiving portion is formed between the body portion of the primary section and the flap 6. 95 Socket members 8 are secured upon the inner surface of the flap 6 and upon the body portions of the primary section 1 at a point upon this primary section which is overlapped by the flap 6. It is of course obvious that these sockets 8 may be spaced as far apart or as close together as desired without departing from the spirit of the present invention.

The auxiliary section 4 has the covering 3 brought together at the abutting end portion 9 thereof and stitched as indicated at 10. The covering is then extended for a

2
 considerable distance to form a projecting flap 11 which may be provided with a stiffening strip 12, carried therein, as shown in Fig. 3 if it is desired to reinforce or 5 strengthen this projecting flap 11 although of course it is obvious this strip is not absolutely necessary in the operation of the invention. As just stated, the projecting flap 11 is formed adjacent the abutting end 9 of 10 the auxiliary section 2 and for this reason projects therebeyond and it will further be noted that the projecting flap is formed in substantial alinement with the top or outer surface of the auxiliary section 2. The ball 15 members 13 are permanently secured upon the projecting flap 11 adjacent the central longitudinal axis thereof and the number of these ball members is intended to correspond with the number of socket members carried 20 upon the primary section and upon the flap 6.

It is of course obvious that if so desired, instead of using the ball and socket connections as before specified, any suitable securing elements, such for instance as buttons and button holes or hooks and eyes may be employed without departing from the spirit of the present invention. It is of course 25 more desirable to use the balls and sockets in view of the fact that no air space is provided through which a draft of air might pass as in the use of buttons and button holes, while the balls and sockets may be more easily secured together when the flaps 30 are brought into overlapping engagement than could possibly be the case, where hooks and eyes are used.

When this invention is in use, the primary and auxiliary sections are positioned adjacent each other to cause the abutting ends 7 and 9 to engage each other. The flaps 6 may then be folded away from the abutting ends 7 and at this time the projecting flap 11 may be swung over the abutting end of the 45 primary section 1 and owing to the formation of this projecting flange 11 at a point adjacent the outer or top surface of the auxiliary section 4, it is obvious the two sections may be brought into direct alinement with 50 each other to form a comparatively even inner surface as indicated in Fig. 3. The ball members 13 upon one surface of the flap 11 may then be brought into a gripping engagement with the socket members upon the 55 body portion of the primary section 1. The flaps 6 may then be swung to overlap and fit upon the projecting flap 11 and at this time the socket members upon the inner surface of the flap 6, will be brought into a gripping engagement with the ball member 13 carried 60 upon the outer surface of the flap 11. By this double connection of the projecting flap 11 with the body portion and also the flaps 6 of the primary section, it is obvious that it 65 will practically be impossible to pull the two

sections apart under ordinary circumstances and for this reason the two sections of the comfort or blanket will be held together.

Special attention is directed to the construction of the flap 6. At a distance from 70 the abutting end of the primary section 1, a substantial internal pocket portion is provided in which the projecting flap of the auxiliary section will extend when the two sections are connected together. This will 75 form a very close connection between the two sections and the flaps so as to provide a connection between the two sections which will prevent a draft of air from passing between 80 the abutting ends of the two sections under any conditions when the device is in use.

By referring to the foregoing description, it will be seen that a very simple and yet very efficient structure has been provided for 85 releasably connecting the two sections of the comfort or blanket together, whereby the sections may be separated for facilitating the easy handling thereof for washing or patching or any other purpose necessary, although when the two sections are connected together 90 the forming of the flaps is such as will prevent the accidental separation of the two sections and at the same time provide a connection which will prevent the passage of 95 an air draft between the abutting ends of the sections.

It is of course obvious that it is not intended to limit the construction of the present invention to the specific form herein shown as only one form of the invention has been 100 illustrated and described and for this reason it is intended to include all such forms of the invention as properly come within the scope of the invention as claimed.

What is claimed is:—

1. A blanket of the class described comprising a pair of sections, said sections including covering thereon, the ends of said sections abutting, the covering of one section being gathered and stitched together at 110 a distance from the abutting end of the section, thus forming a flap extending toward the end of the section, the covering of the remaining section being stitched at the end of the section, thus forming a flap projecting 115 beyond the end of the last mentioned section, said last mentioned flap fitting upon the top of the first mentioned section, and under the first mentioned flap, thus allowing the first mentioned flap to fit upon the top of 120 the last mentioned flap, and means for releasably retaining said flaps and the body of the first mentioned section together, whereby air currents will be prevented from passing through the abutting ends of said 125 sections.

2. A blanket of the class described, comprising a plurality of sections, said sections including covering thereon, the ends of said sections abutting, the covering of one section 130

being gathered and stitched together at a distance from the abutting end of the section, thus forming a flap extending toward the end of the section, the covering of the 5 remaining section being stitched at the end of the section thus forming a flap extending beyond the end of the last mentioned section, said last mentioned flap fitting upon the top of the first mentioned section and under the 10 first mentioned flap, thus allowing the first

mentioned flap to fit upon the top of the last mentioned flap whereby air currents will be prevented from passing through the abutting ends of said sections.

In testimony whereof I affix my signature 15 in presence of two witnesses.

EMMA C. ARNOLD.
